(57) **CLAIM**

The ornamental design for a laser engine with multiple resonators, as shown and described.

DESCRIPTION

FIG. 1 is a perspective view of a laser engine with multiple laser resonators incorporating the design in a first embodiment incorporating six laser resonators;

FIG. 2 is a front view of the embodiment of FIG. 1;

FIG. 3 is a back view of the embodiment of FIG. 1;

FIG. 4 is a left-side elevation view of the embodiment of FIG. 1;

FIG. 5 is a right-side elevation view of the embodiment of FIG. 1;

FIG. 6 is a top view of the embodiment of FIG. 1;

FIG. 7 is a bottom view of the embodiment of FIG. 1;

FIG. 8 is a perspective view of a laser engine with multiple laser resonators incorporating the design in a second embodiment incorporating six laser resonators and a beam-shaping module;

FIG. 9 is a front view of the embodiment of FIG. 8;

FIG. 10 is a back view of the embodiment of FIG. 8;

FIG. 11 is a right-side elevation view of the embodiment of FIG. 8, the left-side elevation view being identical to FIG. 4;

FIG. 12 is a top view of the embodiment of FIG. 8; and, FIG. 13 is a bottom view of the embodiment of FIG. 8.
